(57) **CLAIM**

I claim the ornamental design for an ottoman, as shown and described.

DESCRIPTION

FIG. 1 is a front upper perspective view of an ottoman of Applicant's design;

FIG. 2 is a front elevational view thereof, the rear elevational view being a mirror image thereof;

FIG. 3 is a right-side elevation view thereof, the left-side elevation view being a mirror image thereof;

FIG. 4 is a top plan view thereof; and,

FIG. 5 is a bottom plan view thereof.

The broken lines in the drawings depict environmental structure and form no part of the claimed design.
